(57) **CLAIM**

The ornamental design for a display screen portion with graphical user interface, as shown and described.

DESCRIPTION

The present application is related to U.S. Design patent application Ser. No. 29/623,813 filed Oct. 27, 2017, U.S. Design patent application Ser. No. 29/623,844 filed Oct. 27, 2017, U.S. Design patent application Ser. No. 29/623,815 filed Oct. 27, 2017, U.S. Design patent application Ser. No. 29/623,820 filed Oct. 27, 2017, now U.S. Design Pat. No. D. 847,858, U.S. Design patent application Ser. No. 29/623,826 filed Oct. 27, 2017, U.S. Design patent application Ser. No. 29/670,802 filed Nov. 20, 2018, U.S. Design patent application Ser. No. 29/679,663 filed Feb. 8, 2019, U.S. Design patent application Ser. No. 29/680,898 filed Feb. 21, 2019, and U.S. Design patent application Ser. No. 29/696,743 filed Jul. 1, 2019, the entire disclosures of which are incorporated herein by reference.

The FIGURE is a front view of a display screen portion with graphical user interface showing the new design.

The broken line showing the display screen portion and portions of the graphical user interface image, including text in broken lines, are included for the purpose of illustrating portions of the article and form no part of the claimed design. The dash-dot broken lines depict the bounds of the claimed design and form no part thereof. In the FIGURES, the perimeters of the portion of the underlying display screen and the graphical interface are understood to be flush.
